UNITED STATES PATENT OFFICE.

S. J. PARKER, OF WILLIAMSPORT, PENNSYLVANIA.

IMPROVEMENT IN SHINGLE-MACHINES.

Specification forming part of Letters Patent No. 38,329, dated April 28, 1863.

To all whom it may concern:

Be it known that I, S. J. PARKER, of Williamsport, in the county of Lycoming and State of Pennsylvania, have invented certain new and useful Improvements in Shingle-Machines; and I do hereby declare that the following is a full and exact description thereof, reference being had to the accompanying drawings, making part of this specification.

Figure 1 is a plan of my improved machine; Fig. 2, a side elevation thereof; Fig. 3, a longitudinal vertical section of the same in the plane indicated by the line $x\ x$, Fig. 1; Figs. 4, 5, 6, 7, and 8, views of parts detached.

Like letters designate corresponding parts in all the figures.

The working parts are all mounted in a suitable frame, A. On one side are two similar parallel thin strips of metal, $a\ a$, at suitable distance apart, extending longitudinally of the machine, and forming ways, between which is situated a carriage, B, for holding and guiding the bolt or block from which the shingles are sawed. This carriage is represented in the drawings of rectangular form, and is supported at its bottom by grooved friction-wheels $b\ b$, respectively at its ends, resting on the lower way, while its top is guided and sustained by means of grooved slides $c\ c$, resting similarly against the upper way. The carriage is thus held firmly in place, but allowed to slide freely forth and back. The carriage is provided with a suitable table, d , for receiving the shingle-bolt, and it has on its inside, at the proper position, and situated at suitable distance apart, two vertical feed-rollers, $C\ C$, of a length sufficient to hold against the opposite ends of the bolt, and sustain it in place, and feed it to the saw. These rollers are each made of a hollow cylinder of iron, through the opposite heads of which passes the shaft F, which not quite fills the hollow space, but leaves just sufficient room to allow the projecting points $f\ f$ to be driven through perforations in said cylinder, and thereby clinched against the shaft, so as to hold firmly in place. This device is represented most clearly in Fig. 4, which is a cross-section. The points thus are secured very fast, and always hold in place without becoming loose from shrinkage or other causes, as where wooden rollers are used; and the device is also very cheap. Another

advantage consists in the iron rollers always preserving the same, which is not the case with wooden rollers, the latter swelling when wet and shrinking when dry, thus altering their size, and varying materially the thickness of the shingle sawed from the bolt that they feed forward. The iron rollers always preserve the same size under all conditions; or, if there is any difference in expansion and contraction, it is so slight as not to affect the desired result. The shaft F, of one of the feed-rollers (usually the one next the end of the machine in the drawings) is made stationary, being secured to turn at its upper and lower ends in projections or bearings $g\ g$ of the carriage; but the shaft of the opposite roller rests in similar corresponding bearings, $h\ h$, hinged in such a manner at the outer ends, in the same plane one over the other, Figs. 1, 2, and 3, that the said roller may be expanded or moved longitudinally back from its fellow, for the insertion of a new bolt at any time, or to adapt it to bolts of different lengths. To accomplish this expanding of the rollers, I secure in the same hinged bearings with the last-named roller a vertical shaft, G, having secured thereto, at any suitable position, a central joint-piece, e, which may be made adjustable by means of a set-screw, if desired, and to this joint-piece is hinged one end of a connecting-bar, i, the opposite end being similarly jointed to another rigid joint piece on a sliding rod, H, resting in suitable bearings of the carriage, and between which, around the rod, is situated a coiled spring, k, for holding the said rod down, as shown in Fig. 3. When this rod is raised, the connecting-bar draws upon the shaft G, and consequently on the corresponding feed-roller, thus expanding the rollers, as represented by the red outline in Fig. 3. The sliding rod is raised by means of a similar rod or bar, I, below, over which it rests, thus bringing the respective ends in coincidence, when the carriage is fully drawn back at its reaction. This rod or bar is provided with a spiral spring, in the same manner, to throw it downward; and it is operated by means of a tread-lever, K, convenient to the action of the operator, and whose extremity rests under its end. Thus, when one shingle-bolt is exhausted, and the carriage is fully drawn back, the operator has only to press on the tread-lever to expand the rollers for the insertion of another bolt.

The arrangement is a very convenient and effective one. The two sliding rods H I, by being separate, instead of in one, allow the free movement of the carriage forth and back without any impediment whatever. In addition to this, the inner feed-roller, by being secured in jointed bearings, as described, and turning on the joint-piece e, is adapted to stand in an inclined position, as well as in a vertical one, as represented in the red outline, Fig. 1, so that if the end of the bolt should not be squared exactly square across it can adjust itself to the incline, and bear equally on all parts.

On the upper end of each of the roller-shafts F F is rigidly secured a ratchet-wheel, D, of suitable size, provided with alternately long and short ratchet-teeth, as in other devices for sawing shingles in a similar manner. Directly beneath this ratchet-wheel, and turning freely on the shaft, is situated a crank-arm, E, projecting outward a sufficient distance, and having thereon a pawl, l, held in gear with the ratchet-teeth by a suitable spring. To its extremity is jointed one end of a connecting-arm, L, the other end being similarly jointed to the adjacent end of a vibrating block or cam, M, situated outside the frame. This block is substantially of the arrangement represented in Fig. 1, being pivoted at its inner extremity, m, to a projection, n, of the carriage, and having at its outside two rounded forks or cams, o o, at the proper position, with a depression between. Corresponding in position with these forks is a small friction-roller, q, secured to a rigid arm, r, of the frame. These forks and the friction-roller have such a relative situation that when the carriage is in the act of reacting or being drawn back after completing a cut the forward fork, or that opposite the motion of the carriage, projects so that it will strike the friction-roller, thus throwing the vibrating block around so as to project the opposite fork, and operating the rear stationary feed-roller, by means of its pawl, sufficiently to feed up the bolt the requisite extent for the thickness of the next cut, while at the same time the pawl of the other feed-roller is carried back by the action into gear with the next succeeding ratchet-tooth, ready to be operated. Then, as the carriage goes forward in the opposite direction, feeding up, the rear projecting fork strikes the friction-roller, before the bolt reaches the saw, and operates the inner feed-roller, so as to feed the bolt to the required extent to form the thickness of that end of the shingle.

In the drawings the carriage is represented as going forward and operating the rear fork of the vibrating block. By means of the alternately long and short ratchet teeth the bolt is fed in such a manner as to first saw a "tip" and then a "butt" in front, thus sawing the bolt straight. The arrangement is very compact, simple, and effective, and performs the feeding automatically, while the shingles are sawed in perfect form, straight from the bolt, without loss.

To the lower side of the carriage, and sliding outside the way a, is secured a horizontal rack-bar, N, Figs. 1 and 2, of suitable length for the purpose designed; and into this rack-bar gears a driving pinion, O, coupled to a vertical shaft, P, by which means the forward movement of the carriage is produced. The reaction of the carriage, when this pinion is uncoupled from its shaft, is accomplished by means of a weight connected with a cord passing over a pulley, p, and attached to the carriage at its rear. The shaft P is made cylindrical, and passes through the pinion O, which is made to rise and fall on it, to couple and uncouple, without, however, becoming ungared from the rack-bar under any condition.

To produce the coupling, the top of the shaft above the pinion is provided with a suitable head or cap, having usually two sharp-edged, broad points, s s, Fig. 2, projecting downward from its lower face; and the upper face of the pinion is provided with two or three similar points, which engage with those on the cap when the pinion is raised, but run clear when it is lowered. Directly below the pinion, and in contact with it, is situated a sliding sleeve, Q, having the shaft turning freely within it, but prevented from turning itself by a pin, t, passing down through the bearing in which it rests, or in any other convenient manner. The upper end of the sleeve is provided with a horizontal projecting arm, in the outer end of which is situated a friction-roller, v, Figs. 2 and 6, which rests on a small cam, w, of a horizontal shaft, R, passing through the side of the frame, and having likewise directly under the rack-bar another eccentric or stop b', that forms a stop to a vertical pin, c', secured rigidly to and projecting from the under side of the rack-bar of the carriage, as shown in Fig. 2. On the inner end of the shaft R, inside the frame A, is situated a cam or eccentric, d', Fig. 3, substantially of the form represented, and the use and action of which will presently be explained.

The relative position of the shaft R and its parts is indicated most clearly in Figs. 5 and 6, which are an enlarged plan and end view, detached.

On the inside of the frame, and at a suitable position to correspond with the necessary length of stroke of the carriage, is situated a curved sliding stop bar, S, substantially of the shape represented in Fig. 3—that is, with the curved or convex portion of suitable length for the purpose designed, provided with right-angled shoulders or notches a' a', situated near together, and with the front and rear portions of the bar made straight, the latter constituting a shank, l', resting and sliding in a guide, f', and the former having a straight, horizontal slot, g', in which rests a right-angled arm, h', from the frame, or some equivalent means of holding it and allowing it to slide. To the shank l' is attached a cord passing over a pulley, i', and having a weight

secured to its opposite end, by which means the stop-bar is drawn back, except when it is acted on by positive force. To the side of the stop-bar, at a suitable position in the rear, is secured a shoulder, k' , substantially of the shape shown in Fig. 3, and forming a stop for striking against the cam d' of the eccentric-shaft, for the purpose presently to be explained. From the rear, lowermost notch or shoulder a' of the stop-bar extends upward and backward a plane, inclined track, or way, T , Figs. 1 and 3, to a suitable height for the purpose intended, and to a distance corresponding with the position of the rear of the carriage when drawn entirely back. On this track rests the end of a gage-rod, U , Fig. 3, sliding freely through bearings $m' m'$ from the carriage, and having at a suitable position above a horizontal arm, n , projecting over the bolt, and which, in turn, may be provided with a right-angled projection, o' . The arm may be adjustable on the gage-rod, if desired, by means of a set-screw, so as to raise or lower it. The projection o' rests on the top of the shingle-bolt, whether it is large or small, thus holding the lower end of the gage-rod stationary in a corresponding high or low position, as the carriage moves forward.

The action of the parts above described for producing the automatic reciprocations of the carriage and for gaging their length is as follows: Suppose the coupling-pinion O to be in gear with its shaft, and the carriage to be moving forward, as indicated by the arrows in Figs. 2 and 3. As it moves, the gage-rod U will follow down its inclined track by its weight till the projection o' rests on top of the shingle-bolt, whether large or small, and in this position (either high or low) will be retained till the forward edge of its lower end strikes against one of the shoulders a' of the stop-bar S . The point at which it strikes the curve of the stop-bar, and consequently the length of the reciprocation of the carriage, is determined by its height, or, in other words, the size of the shingle-bolt, a large bolt allowing a larger stroke of the carriage, and vice versa. Thus the length of stroke of the carriage is so adapted that a large bolt runs a greater distance by the saw V covering a greater extent of its radius, and this is necessary to cut the shingle free, while a small bolt runs a less distance, and thus unnecessary expenditure of power, labor, and time are saved. As soon as the lower end of the gage-rod strikes either of the notches of the stop-bar, the latter is forced forward, thereby bringing the shoulder k' against the end of the inclined eccentric d' , turning the latter upward into the position indicated by red lines, Fig. 3, and turning its shaft R sufficiently to remove the concentric portion of the cam w , from beneath the friction-roller v of the sliding sleeve Q , thereby allowing the said roller to fall down the abrupt side of the cam, and thus depressing the pinion O sufficiently by the action to uncouple it from its shaft P , and so

releasing the carriage and allowing it to be carried back by the weight attached to it. The position of the parts when thus uncoupled is indicated by the red lines in Fig. 6. At the same time that the shaft R is turned to uncouple the pinion its stop b' is turned up into the position represented by the red lines, and at the end of the backward reciprocation of the carriage the vertical pin c' , projecting from the under side of the rack-bar, strikes against this stop, forcing it back into its original position, and consequently turning the cam w so as to raise the driving-pinion and bring it in couple again. Thus, not only are the reciprocations of the carriage automatic, but their length is also gaged to adapt them to sawing bolts of different sizes.

In order to stop the carriage for the insertion of a new bolt, or for any other purpose, the eccentric-shaft R is provided with a small crank, p' , inclining downward and backward, as represented in Figs. 2 and 6, to which is jointed a connecting bar, W , extending outward a suitable distance, and having a slot, q' , of suitable length for the purpose designed in its opposite end, through which passes the pivot of a rigid arm, A' , secured to a horizontal rock-shaft, B' , resting in suitable bearings, $r' r'$, and having inside a lever, C' , by which the whole is operated. The lever works within a suitable gage-iron, D' , Fig. 1, by which its motion is limited in either direction; and the latter has also an intermediate stop, s' , near the inner end, for holding the lever in that position, for a purpose that will be presently explained. The slot q' in the outer end of the connecting-bar W is of just such length as to allow the automatic action of the eccentric-shaft R without any interference therewith, when the lever C' is thrown outward in the position indicated in the drawings; but when the lever is thrown inward in the opposite direction the rigid arm A' forces the connecting-bar inward, thereby operating the crank p' , and turning the cam w backward, or in the direction opposite its automatic action, as indicated by the dotted lines in Fig. 6. This same action also consequently throws the eccentric d' in the direction opposite its automatic motion, as shown by dotted lines in Fig. 3. If the lever is moved forward its whole extent, the concentric portion of the cam w is thrown back entirely from under the friction-roller, allowing the latter to fall over the abrupt forward edge of the same, consequently instantly uncoupling the driving-pinion, and stopping the carriage at any point, as in case of accident of any kind; but if the lever be moved forward only to the stop s' of its gage-iron the cam w will be moved only just sufficiently backward to allow the friction-roller to rest on the extreme forward part of its concentric portion, and the eccentric d' , Fig. 3, will only be turned downward in an inclined direction, instead of vertically, so that when the shoulder k' strikes it it forces it entirely around, and thus uncouples

the carriage. Thus, by setting the lever C' in the stop s' at any time during the last cut of a bolt, the carriage will be disengaged at the end of the cut by the automatic action, and remain in that condition till a new bolt is in place, when, by moving the lever back, the automatic action of sawing goes on as before.

To the lower end of the driving-shaft P is secured a spur-wheel, Q', which turns freely and loosely thereon; and into this wheel gears the threads of an endless screw, E', whose shaft F' receives its motion by means of a band from the main saw-shaft G', running on a set of cone-pulleys, or in any other convenient manner. Thus the spur-wheel, and consequently its driving-shaft, is constantly moved in one direction by the screw during all the actions of the machine. In the reaction of the carriage, therefore, the pinion O, being uncoupled from its shaft, is turning in one direction, while the shaft itself is turning in the opposite. At the moment of coupling the pinion with the shaft again, for a new cut, the parks thus moving opposite each other would be subject to a great shock and strain when brought together, were not provision made to obviate the difficulty. To accomplish this, I rigidly secure to the lower end of the shaft P a cross-head, H', directly over the cog-wheel, substantially represented in Fig. 7, (which is a plan,) and the top of the wheel I make hollow or dishing, and locate therein a spiral flat spring, I', one end being secured to the wheel and the opposite to the cross-head. On opposite sides of the upper surface of the spur-wheel are situated two projecting pins, t' t', which, when the carriage is going forward, wind up the spring and strike against the ends of the cross-head, and cause the shaft to revolve; but when the carriage reacts the spring expands and throws the cross-head around in the opposite position. Thus, when in this latter position, at the moment that the pinion is engaged with the shaft again, the spring must be taken up, and the cross-head must be moved around to the pins again, thus breaking the shock and easing the coupling before the parts act together. This arrangement is essential to the machine, which is inoperative without it. As fast as the shingles are sawed, they fall on a bed or table, K', inside the saw, from which table they are easily removed. After being sawed from the bolt, the rough and unequal edges of the shingles are to be cut or planed at right angles, to render them fit for use. To accomplish this, I employ a circular dressing-wheel, L', Figs. 1 and 8, of peculiar construction. The wheel is cast with alternate oblique ribs w' w' and intermediate space or depressions, v' v', substantially of the shape and position as represented most clearly in Fig. 8. The ribs are ground down to a perfectly plane, smooth surface on an emery-wheel, which is much less labor and cost than when the whole face of the wheel is plane, while the ribbed wheel is much more effective in operation, as will be directly described.

The face of the wheel is provided with knives w' w' at proper points to plane the edge of the shingles, and with suitable throats for the escape of the shavings. Across the ribbed face of the wheel is situated an inclined table, M', provided with a stop at its bottom for receiving and holding the shingle properly to the knives. As these revolve, they cut away the edge of the shingle, while the depressions between ribs also assist in the escape of the shavings and splinters that would otherwise clog and prevent the effective operation of the knives. The dressing-wheel receives its motion by a band from the main saw-shaft, or in any convenient manner.

What I claim as my invention, and desire to secure by Letters Patent, is—

1. The vibrating block M, provided with the forks o o, and connected with the ratchet-wheels D D by means of the connecting-arms L L, crank-arm E E, and pawls l l, when the same is operated by means of the stationary friction-roller q, or its equivalent, in such a manner that the carriage is allowed a free movement forth and back, and the said ratchet-wheels are actuated equally, whether the reciprocations are long or short, the whole arranged, combined, and operating substantially as herein set forth.

2. The feed-roller C, made of a hollow metallic cylinder, with the shaft F passing through it and with perforations in its periphery, through which are driven the points f f, clinching against the shaft, the whole arranged as described, so that the roller is unaffected under all conditions, and feeds the bolt equally and uniformly, substantially as specified.

3. Securing the shaft F of the forward feed-roller in hinged bearings h h, and bracing it against side movement by means of a central jointed bearing, e, which allows it to adapt itself with equal pressure to an inclined or uneven end of the shingle bolt, substantially as herein described.

4. In combination with the feed-roller supported by hinged bearings h h, the vertical shaft G, jointed connecting-bar i, and sliding rod H for expanding the rollers for the inserting the bolt, the whole arranged and operating substantially as herein set forth.

5. The combination of the two separated spring sliding rods H and I, so arranged that they allow the carriage to slide freely forward and back without impediment, but come in coincidence when the said carriage is drawn fully back, so that the feed-rollers may be expanded by their action, substantially as herein described.

6. In combination with the curved sliding stop-bar S, having notches a' a', or their equivalent, the adjustable gage-rod U, provided with the horizontal arm n', the whole arranged so that the length of stroke of the carriage is adapted to the size of the bolt to be sawed, substantially as herein set forth.

7. In combination with the subject-matter of the preceding clause, the inclined track or

way T, arranged substantially as and for the purpose herein described.

8. The shoulder k' of the stop-bar S, the eccentric d', stop b', cam w, and sliding sleeve Q, provided with the friction-roller v, or its equivalent, in combination with the pinion O, for the purpose of coupling and uncoupling the latter to and from its shaft, arranged substantially as herein described.

9. Connecting the eccentric-shaft R with the vibrating lever C' by means of the inclined crank p', connecting-bar W, provided with the slot q', arm A', and rock-shaft B', the whole arranged and combined in such a manner that the said eccentric-shaft is turned backward by the action of the lever, so as to permanently

uncouple the driving-pinion at any time, and so that the automatic action is carried on without impediment, substantially as herein specified.

10. The cross-head H' of the driving-shaft, in combination with the spur-wheel D', provided with the pins t' t', and the spiral spring I', arranged and operating substantially as and for the purposes herein set forth.

In witness whereof I have hereunto signed my name in the presence of two subscribing witnesses.
